DESIGN FOR A PORTABLE WASHING MACHINE

William L. Pressey, Chicago, Ill., assignor to Odisco Corporation, Chicago, Ill.

Application March 12, 1938, Serial No. 75,782

Term of patent 14 years

To all whom it may concern:

Be it known that I, William L. Pressey, a citizen of the United States, residing at Chicago, in the county of Cook and State of Illinois, have invented a new, original, and ornamental Design for a Portable Washing Machine, of which the following is a specification, reference being had to the accompanying drawing, forming part thereof.

In the drawing:

The figure is a perspective view of a portable washing machine showing my new design. The other side is like the side shown.

I claim:

The ornamental design for a portable washing machine, as shown and described.

WILLIAM L. PRESSEY.
